Primary Examiner—Brian N. Vinson
Attorney, Agent, or Firm—Connolly & Hutz[57] **CLAIM**

The ornamental design for an octopus towel rack, as shown and described.

DESCRIPTION

FIG. 1 is a front elevational view of an octopus towel rack in accordance with this design, it being understood that the rear elevational view is the same but without eyes and eyebrows;

FIG. 2 is a right side elevational view thereof, it being understood that the left side elevational view is a mirror image duplicate;

FIG. 3 is a top plan view; and,

FIG. 4 is a bottom plan view thereof.
